L. FUCHS.
SURFACE INDICATOR.
APPLICATION FILED JULY 31, 1909.
1,079,169.

Patented Nov. 18, 1913.

UNITED STATES PATENT OFFICE.

LEON FUCHS, OF DAYTON, OHIO.

SURFACE-INDICATOR.

1,079,169.

Specification of Letters Patent. Patented Nov. 18, 1913.

Application filed July 31, 1909. Serial No. 510,685.

To all whom it may concern:

Be it known that I, LEON FUCHS, a citizen of the United States, residing at Dayton, in the county of Montgomery and State of Ohio, have invented certain new and useful Improvements in Surface-Indicators, of which the following is a specification.

My invention relates to measuring instruments and particularly to test indicators for measuring the variations of surfaces over a given plane or arc.

The object of the invention is to simplify the structure as well as the means and mode of operation of such instruments whereby they will not only be cheapened in construction but will be more sensitive and efficient in use, easily operated, and unlikely to get out of repair.

A further object is to provide such an instrument which will be universal in its adjustments; that is, capable of being operated at any angle and in which the indicator scale will always be maintained in position to be readily observed by the operator.

25 A further object is to provide improved means for maintaining the instrument in its adjusted position.

With the above primary and other incidental objects in view as will more fully appear in the specification, the invention consists of the feature of construction, the parts and combinations thereof and the mode of operation or their equivalents, as hereinafter described and set forth in the 35 claims.

Referring to the drawings, Figure 1 is a perspective view of the assembled instrument in operative position. Fig. 2 is a side elevation of the instrument showing in 40 dotted lines the adjustment of the contact member to different radial positions. Fig. 3 is an end elevation of the instrument showing in dotted lines the oscillatory adjustment thereof. Figs. 4 and 5 are interior 45 views of the opposite halves of the circular head showing the operative mechanism. Fig. 6 is a sectional view through the head showing the operating mechanism assembled. Fig. 7 is a transverse sectional view through the head. Fig. 8 is a detail view of the frictional adjustment shoe.

Like parts are indicated by similar char-

acters of reference throughout the several views.

In constructing the device there is employed a circular head or casing comprising two engaging relatively movable parts 1 and 2. The said parts are provided with inter-engaging rabbets as shown in the sectional view, Fig. 7, the rabbet of one of said parts 55 being provided with a peripheral groove 3 engaged by a plurality of screws 4 in the other portion of the head whereby the portion 2 thereof may be rotated upon the portion 1 and will be maintained in engagement therewith by means of the screws 4 projecting into the peripheral groove 3. The head portion 1 is provided with an integral shank 5 which telescopes within a handle portion 6 and is secured therein by a set 60 screw 7. The handle portion 6 is rectangular in cross section and is adapted to be held in the tool post or other tool holding device of a lathe, planer or shaper, whereby the contact member hereinafter mentioned may 65 be brought into engagement with the work. The handle portion 6 is also provided with a transverse opening 8 and a set screw 9 by which the instrument may be secured upon the supporting stand of a surface gage or 70 secured to other supporting means. The shank 5 is both longitudinally and revolvably adjustable within the portion 6. The head portion 1 is also provided with a wing extension 10 located on the upper side of the 75 head and bearing graduations which may indicate any suitable unit of measure which graduations preferably represent thousandths of an inch corresponding to the variations of the contact member as it passes over the 80 surface of the work being tested. Within the interior of the head section 1 there is journaled on a stud 11 a gear member 12. The gear member 12 is provided with a shouldered shaft 13 screw threaded at its 85 outer extremity and formed integral with the gear member 12 or rigidly secured thereto. The shaft 13 is preferably provided with a bore at its inner extremity or within the hub of the gear member 12 within which the pivotal stud or trunnion 11 projects. The gear member 12 meshes with a gear pinion 14 journaled in suitable bracket 15 and carrying an indicator hand or pointer 90 95 100

16 which oscillates over the scale located on the wing extension 10. The indicator hand or pointer 16 has formed therein a bight or bend 17 so located that the hand may be oscillated throughout the full width of the wing extension 10 without interfering with the shaft 13 or parts carried thereby. A hair spring 18 is attached to a suitable screw within the casing member and extends about 10 the casing and engages the gear pinion 14 and tends to move said pinion whereby the indicator hand 16 will be oscillated toward the left in Figs. 4 and 6. The engagement of the hair spring 18 with the gear pinion 14 is preferably by means of a right angled bend at the extremity of the spring which engages a small hole in one of the teeth of the gear pinion. However, this spring may be otherwise engaged with the pinion and 15 might be otherwise located than as shown in the drawings. For instance, it might be in the nature of a coil spring such as used in watch constructions.

Loosely journaled on the shaft 13 and 20 abutting the shoulder 19 thereof is a gear segment 20. Screw threaded on the extremity of the shaft 13 is a knurled clamping nut or sleeve 21 and interposed between the nut or sleeve 21 and the gear segment 25 20 is a washer 22. The construction is such that when the clamping nut or sleeve 21 is loosened the gear segment 20 will be free to rotate upon the shaft 13 and may be oscillated thereon to any desired position in 30 which it will be securely locked by the tightening of the clamping nut or sleeve 21. Within the section 2 of the head or casing there is provided a reciprocating rack 23 having longitudinal extensions 24-25 provided with bearings in suitable guides or 35 supports 26. Connected with the extension 24 is a helical spring 27 which tends to push the rack member 23 outward. Secured in the casing member 2 by screw threading or 40 otherwise is a sleeve 28 through which extends a contact stem 29 which forms the "feeler" or operating point which engages the work. When the two parts of the head or casing are engaged the rack member 23 45 engages the gear segment 20 located on the shaft 13 of the gear member 12 as particularly shown in Fig. 6. When so engaged, any reciprocating movement of the stem 29 due to irregularities in the surface of the 50 work over which the instrument is being moved will be transmitted to the indicator hand 16 and will oscillate said hand 16 over the scale contained on the wing extension 10 to indicate the degree or extent of such 55 irregularity. The construction is such as to multiply the degree of movement whereby a very slight movement of the contact stem or 60 feeler 29 will produce a considerable movement of the indicator hand 16 thereby readily showing the variation. The move-

ment is transmitted from the contact stem or feeler 29 to the gear segment 20 by means of the rack 23 with which the stem 29 is rigidly secured. The gear segment 20 is fixed in its relation to the gear member 12 70 by being impinged between the shoulder 19 of the shaft 13 and the washer 22 thereon by means of the clamping nut or sleeve 21 whereby the oscillatory movement of the gear segment 20 caused by the reciprocating movement of the rack 23 will move the gear member 12 in unison therewith. The gear member 12 being intermeshed with the gear pinion 14 which is of very much 75 less diameter, causes a relatively greater oscillation of said gear pinion 14 which in turn carries the indicator hand 16 rigidly secured thereto.

The movement of the various parts thus described is against the tension of the hair 80 spring 18 and also the helical compression spring 27. On account of different positions of the surface of the work to be tested it is desirable to adjust the instrument to different angular positions. The contact 85 stem or feeler 29 is adjustable to different radial positions by the rotation of the casing member 2 as shown by dotted lines in Fig. 2. By radially adjustable is meant the capability of being adjusted to positions 90 corresponding to different radii about a common center. This is accomplished by first releasing the compression nut or sleeve 21 and then rotating the casing member 2 until the contact stem or feeler 29 is in the 95 desired positions.

For the purpose of accurately adjusting the angularity of the contact stem there is provided about the periphery of the head or casing a scale 30 divided into degrees. 100 When the compression nut or sleeve has been released the gear segment 20 is free to turn upon the shaft 13 with the head section 2 to the new position where it is again secured by the tightening of the sleeve or nut 21. 105

In order that the parts may not move too freely and thereby increase the difficulty of accurate work a frictional contact or brake device is provided comprising a shoe 31 conforming to the exterior of the revolute 110 head section 2 and secured upon the shank 5 by dependent ears 32. Adjacent to the shoe 31 is a tapered screw 33 screw threaded into the shank 5 and bearing on the outer side of said shoe. By tightening the tapered 115 screw 33 the friction shoe 31 is forced into contact with the exterior surface of the revolute head member 2 affording a slight 120 resistance to the rotation thereof.

In addition to the adjustment to different 125 radial positions of the contact stem or feeler 29 the entire head of the instrument may be adjusted to different radial positions about the shank 5 by loosening the set screw 7 whereby the shank 5 may be rotated within 130

the portion 6, such adjustment being shown by dotted lines in Fig. 3.

For testing the interior surface of small parts or the interior of a bore there is provided a split collar 34 Fig. 5 adapted to be engaged upon the extremity 35 of the sleeve 28. The collar 34 is provided with an arm 36 extending parallel with the sleeve 28 in which is pivoted a bell lever 37 having equal arms, one arm of which bears upon the extremity of the contact stem or feeler 29 while the opposite arm which is provided with a substantially spherical head 38 is adapted to engage the work. It is obvious that any irregularities in the surface engaged by the side of the head 38 will cause an oscillation of the bell lever 37 which in turn will cause a corresponding reciprocatory movement of the contact stem 29. The stem 29 is provided with a spherical head 39 for contact with the work. The spring 27 presses the contact member 29 into engagement with the surface of the work whereby the spherical head 39 will follow the variations of the surface from a common plane, the movement of the contact member 29 being against the tension of the spring 27. The movement of the rack 23 due to the extension of the spring 27 would also tend to move the indicator hand to the left in the various figures of the drawings. However, on account of the great accuracy required in an instrument of this character it is not practical to depend upon such construction because however careful the respective gear members 12 and 14 may be cut there will be more or less lost motion between said members whereby the indicator might respond promptly to slight variations in the contact member 29 and rack 23. To obviate this difficulty a special hair spring 18 is provided which tends to move the indicator hand to normal and any movement of the indicator is against the tension of the spring 18. The spring 18 further holds the teeth of the gear pinion 14 in close engagement with those of the gear member 12 and thereby prevents any trim of the indicator hand which would render the reading of the indication more difficult. In other words, the spring 18 causes the indicator hand to move positively with the actuating parts. In order that the indicator hand 16 may not be subject to strain as it approaches the limit of its movement in either direction the rack 23 is limited in its movement by the engagement of the shouldered extremities thereof with the interior surfaces of the supports 26. Thus the supports 26 limit the movement of the rack in either direction and thereby limit the movement of the indicator hand.

The instrument is adapted to be secured rigidly in a suitable support such as a tool post or support or other clamping device,

in such relation to the work that the work will be engaged by the contact 29 or 38, according to the nature of the piece of work to be tested. The instrument and support may be moved in a predetermined path relative to the work held in a stationary position or the work may be caused to travel past the instrument. Any inequalities or variations in the surface of the work over which the contact passes will cause a reciprocatory movement of the member 29 which will be transmitted to the indicator which by its movement over the scale will indicate the degree of irregularity. By adjusting the contact to different angular positions as shown in Fig. 2, the instrument may be employed to test surfaces in various positions of angularity.

From the above description it will be apparent that there is thus produced an instrument of the character described possessing the particular features of advantage before enumerated as desirable which obviously is susceptible of modification in its form, proportion, detail construction and arrangement of parts, without departing from the principle involved or sacrificing any of its advantages.

Having thus described my invention I claim:

1. In a measuring instrument, two relatively rotatable supporting members movable in parallel planes about a common axis, a contact member capable of reciprocatory movement carried by one of the members, a variable indicator carried by the other supporting member indicating by its degree of movement the degree of reciprocatory movement of the contact member, actuating connections between the contact member and indicator, said contact member being adjustable to various radial operative positions independent of the indicator by the relative rotation of the supporting members and means for locking the supporting members one with the other, substantially as specified.

2. In a measuring instrument, two relatively rotatable supporting members movable in parallel planes about a common axis, an actuating member operated by the irregularities of the work operated upon carried by one supporting member, a variable indicator carried by the other supporting member intermediate connections between the actuating member and indicator whereby the indicator will be actuated by the movement of the actuating member to indicate the degree of irregularity of the work operated upon, said actuating member being adjustable to sundry undetermined radial positions in a common plane independent of the indicator by the relative rotation of the supporting members and means for locking the supporting members in adjusted position, substantially as specified.

3. In a measuring instrument, a head comprising two supporting members capable of being engaged one with the other and relatively rotatable in parallel planes when disengaged one from the other, an indicator carried by one of the members, a movable member carried by the other member and adapted to be actuated by its passage over irregularities in the surface of the work operated upon, actuating connections between the movable member and the indicator whereby the indicator will disclose the relative degree of movement of the movable member due to the irregularities in the surface of the work.

4. In a measuring instrument, a head comprising two relatively rotatable sections capable of being engaged one with the other and rotatable in parallel planes when disengaged one from the other, an oscillatory indicator carried by one of the sections, a movable member capable of reciprocatory movement carried by the other section and adapted to be reciprocated by the irregularities in the surface of the work over which the instrument is operated intermediate actuating connections between the said movable member and the indicator whereby a reciprocatory movement of the movable member will cause a corresponding oscillatory movement of the indicator, said indicator and movable member being relatively adjustable to different operative positions in parallel planes by the relative rotation of the said head sections, substantially as specified.

5. In a measuring instrument, a head comprising two parallel sections relatively rotatable in relation to each other in parallel planes, an indicator carried by one of the sections, a revolute gear member journaled concentric with the axis of rotation of the relatively rotatable head sections, and adapted by its oscillation to actuate the indicator, a rack member capable of reciprocatory movement carried by the other head section and meshing with said gear member in all positions of revolute adjustment of the relatively rotatable head sections, and adapted by its reciprocation to oscillate the gear member to actuate the indicator, and a movable contact member adapted by its engagement with irregularities in the surface of the work operated upon to reciprocate said rack member, substantially as specified.

6. In an instrument of the character described, a casing, a movable contact member, a multiplying gear train, an indicator hand operated thereby, a drive shaft, a gear pinion loosely journaled on said shaft, a rack movable with said contact member and engaging said gear pinion, said contact member being radially movable relative to said shaft, means to engage the gear pinion with the drive shaft whereby the gear train will

be operated thereby, substantially as specified.

7. In an instrument of the character described, a casing, a gear member revolvably mounted in said casing, a shaft movable with said gear member, a gear pinion with which the gear member meshes, an indicator hand carried by the gear pinion, a second gear pinion adjustably mounted on said revolute shaft, a reciprocating contact member, a reciprocating rack movable therewith and engaging the adjustable gear pinion on the revolute shaft, whereby a reciprocatory movement of the contact member will cause a corresponding movement of the indicator through an increased degree regardless of the radial direction of the reciprocatory movement, substantially as specified.

8. In an instrument of the character described, a casing, a gear member revolvably mounted in said casing, a shaft movable with said gear member, a gear pinion with which the gear member meshes, an indicator hand carried by the gear pinion, a second gear pinion revolvably adjustable on the said shaft, means for securing the pinion in its adjusted position on the shaft, a radially movable reciprocating contact member, a rack movable therewith and engaging the adjustable gear pinion, whereby a reciprocatory movement of the contact member will be transmitted to the indicator, substantially as specified.

9. In a measuring instrument, a head divided into two relatively movable portions, a movable contact member carried by one of the head portions, a variable indicator carried by the other of the head parts, intermediate connections whereby the indicator is actuated by the movement of the contact member, a friction shoe carried on one of the head portions and bearing on the other head portion and affording resistance to the free movement thereof, substantially as specified.

10. In an instrument of the character described, an oscillating indicator, an indicator scale with which the indicator co-operates, a reciprocatory contact member capable of oscillatory adjustment independent of the indicator, the indicator scale and contact member being angularly adjustable in a substantially common plane, and an intermediate connection between the indicator and contact member whereby the indicator will be operated by the movement of the contact member in all positions of its angular adjustment in relation to the indicator, substantially as specified.

11. In a measuring instrument, a reciprocatory contact member pivotally supported whereby the contact member may be oscillated to different radial positions independent of its reciprocatory movement, a support for the contact member, an indicator carried by

the support, variable actuating connections between the contact member and indicator whereby the indicator will indicate the degree of reciprocatory movement of the contact member in all positions of adjustment about its pivotal connections.

5 In testimony whereof, I have hereunto

set my hand this 20th day of July, A. D. 1909.

LEON FUCHS.
